UNITED STATES PATENT OFFICE

JAMES P. GILLIGAN AND GEORGE W. EDWARDS, OF TOLEDO, OHIO

AUTOMATIC TRAIN CONTROLLING APPARATUS

Application filed January 18, 1927. Serial No. 161,908.

Our invention relates to automatic train dependent upon the energization of the sole-
controlling apparatus and has to do with the provision of novel control devices which co-
operate with the air brake equipment of the

train and which will not only positively con-
5 trol the stopping of the train under condi-
tions of extreme danger and when the block
indicates stop, but will also be effective to
stop the train when the usual trackside sig-
10 nal fails to indicate existing danger condi-
tions. It also results in important safety
measures in that the automatic stop devices
will, in normal operation, effectually and
automatically stop the train within effective
15 safety limits and braking distance from any
danger or block points.

Our invention has to do primarily with the
provision of means for positively releasing
the air in the air brake system so as to ensure
a positive stopping of the train at a safe dis-
tance from any point of danger. This stop-
20 ping of the train is accomplished by means
of very simple, compact and positively act-
ing structure which comprises electrically
controlled means carried by the train and op-
erated by striking a ramp, third rail, or other
25 object which is not charged, means for auto-
matically charging said rail in the event that
the track is safe and the train is to proceed,
and solenoid control means for releasing the
air brake pressure of the train whenever the
30 third rails are automatically de-energized or,
if for any reason, there is a broken circuit
leading to the third rails or within the elec-
trical system carried by the train. The third
rails for controlling the stopping of the train
35 are, under normal safe conditions, connected
with a current supply and such current sup-
ply is, preferably, broken only in the case
of danger to the train resulting, for instance,
from the train entering an already occupied
40 block or section.

One of the objects of our invention is the
provision of an air brake valve, cylinder and
piston construction for operating such valve
and solenoid operating means for normally
maintaining said piston structure in inoper-
45 ative position. The result is that the move-
ment of the piston structure for opening the
air brake valve to stop the train is entirely

whereby any deenergization of the sole-
noid will permit the actuation of the piston
structure to open the valve.
A further object of our invention is the 55
provision of automatically operating means
for controlling the stopping of the train
when going in one direction only and the
provision of additional automatic stopping
means for controlling the stopping of the 60
train when going in the opposite direction.
In this case, when one of such devices strikes
a "dead" third rail, the train will be stopped.
Such particular stopping device would not
affect the progress of the train in the oppo- 65
site direction or, in other words, when the
train is going forward, the third rails on
one side of the track control only such for-
ward movement of the train while the third
rails on the opposite side of the track control 70
the rearward movement of the train. Fur-
thermore, we have thus provided a means
whereby, when the train is positively stopped
by the automatic stop device, the trainman
may descend from the locomotive and adjust 75
the air control valve and then back up his
locomotive without causing his train to be
again stopped by such particular automatic
stopping device.

A further object of our invention consists 80
in the provision of an air brake control valve
for releasing the air brake pressure in the
brake pipe system and balanced fluid and
solenoid control means for moving the air
control valve in one direction only. The re- 85
sult is that, when the solenoid is deenergized,
the fluid control means will be effective to
open the valve to stop the train, but the re-
energization of the solenoid will not be effec- 90
tive to close the valve. Thus, the valve must
be closed manually, while it may be opened
automatically.

A still further object of our invention has
to do with the provision of a pivoted trolley
with contact closing members of unequal 95
length on either side of the trolley whereby,
when the trolley is moved in one direction,
the shorter member will break the circuit
carried by the train and, when the trolley
member is moved in the opposite direction, 100

the longer contact member will maintain the circuit, carried by the train, closed. The result is that, when the trolley member is moved in one direction by striking the third rail, the current for energizing the solenoid will either be supplied by such third rail or the solenoid core will be released to effect stopping of the train. However, if the trolley is moved in the opposite direction, the longer contact member will be effective to maintain the train circuit closed and to maintain the solenoid energized.

Another object of our invention has to do with the provision of a switch or contactor mechanism in connection with the regular track switch and which is so arranged that the contactors for supplying current to the third rail will be resiliently held in position until positively moved by the track switch to non-contacting or danger indicating position. In this case, the instant the track switch is moved to a danger indicating position, the current supplied to the third rail will be immediately cut off to automatically effect stopping of the train.

Another object of our invention has to do with the provision of means for keeping the third rails clean at all times, regardless of weather conditions, to ensure positive electrical contact between the third rails and the trolley structure for controlling the release of the solenoid core.

A further object of our invention has to do with the provision of a cut-out valve equipped with electrical control means whereby any one of the train stopping devices on a plurality of locomotives may be rendered inoperative.

Many other features of our invention will be apparent as this description progresses and will be brought out in the claims appended hereto. The various objects of our invention are, preferably, obtained by the structure illustrated in the drawings wherein similar characters of reference designate corresponding parts and wherein

Figure 1 is a diagrammatic side elevation of parts of a locomotive which is equipped with our automatic stopping mechanism also diagrammatically shown.

Figure 2 is a side elevational view of a cut-out valve, and the switch for connecting the trolley to the solenoid to keep the solenoid constantly charged.

Figure 3 is an enlarged detail view of the trolley structure shown in Figure 1, showing the unequal contact members carried by the trolley and the resilient mechanism for cleaning the third rails.

Figure 4 is a fragmentary horizontal cross-section taken on line 4-4 of Figure 3, showing means for insulating the trolley member against electrical contact with the locomotive.

Figure 5, is a diagrammatic layout of the

trackside circuit as associated with a rail switch, such circuit operating in conjunction with the locomotive circuit also diagrammatically shown.

Figure 6, is a diagrammatic layout of the trackside circuit as associated with a semaphore controlling one of the blocks along the right of way.

In the drawings, our automatic train stopping device is shown as comprising a valve 1 which controls the release of the air brake pressure in the air brake system for stopping the train. This valve 1 is obviously carried by the locomotive but, in Figure 1, we have diagrammatically shown this valve with the air brake and electrical brake controlling mechanism of the locomotive.

As best shown in Figure 1, the air control valve is connected to a standard air brake pipe 2 of the locomotive. The valve is, preferably, provided with an operating cam element 3 which cam element is designed to be moved in one direction only by means of a suitable piston rod 4, which piston rod forms a part of the piston 5 which is, in turn, designed to reciprocate within a suitable air cylinder 6. The piston rod 4 is not connected with the valve cam element 3 but is merely designed to contact with one face of such cam element to move said cam element and the valve to open position to release the air brake pressure.

The piston rod 4 is pivotally connected to one end of a lever 8 which is fulcrumed on the locomotive frame as at 9. The lower end of this lever 8 is preferably pivotally connected to a rod 10 whereby any oscillation of the lever 8 will be effective to move the rod 10 horizontally within its bearing supports or, in other words, the lever 8 may be oscillated about the fulcrum 9 while the rods 4 and 10 connected thereto are horizontally reciprocable. The rod 10 is connected at one end to the solenoid core 11. This solenoid core 11 forms a part of a suitable solenoid 12.

As best shown in Figure 1, the piston 5 and cylinder 6 are directly connected with the air brake pressure pipe 2 whereby the normal air brake pressure in the pipe 2 is designed to be constantly effective upon the piston 5. However, in the normal operation of our device, the electric current passing through the solenoid 12 will be effective to produce enough "pull" upon the solenoid core 11 so that the tendency of the air brake pressure to move the piston 5 will be overcome as long as the solenoid 12 is energized.

At the instant the solenoid 12 is deenergized for any cause whatever, the pulling force upon the solenoid core 11 will be obviously released and the air brake pressure upon the piston 5 will be effective to move such piston and its piston rod 4, whereby such piston rod 4, contacting only with the surface of the valve cam 3, will move the valve

lever to open the valve 1 and release the air pressure in the air brake pipe 2 to stop the train. Our device is provided with a valve 1^a operated by the rod 4^a when the valve 1 is operated. The valve 1^a will release the air pressure contained in the main reservoir 60 through the pipe 2^a and so obviate any possibility of recharging the brake pipe 2 as long as the valve 1^a is open.

10 An independent brake valve 31^a is also shown in Figure 1. This brake valve is manually operated by means of the lever 34^a and may be used independently of the automatic brake control.

15 In Figure 1, we have shown a trolley 13 pivoted to the forward part of the locomotive frame as at 14 and held in normal vertical position by the coil spring 50 (see Figure 3). As best shown in Figures 1 and 3, this pivoted trolley is normally designed, when in vertical position, to act as a contact switch for connecting a contact 15 with a contact 16. As particularly shown in Figure 1, the contacts 15 and 16 are separated and the connection between said contacts is designed to be effected by means of a contact member 17 carried by the trolley 13. It will be noted that the contact member 17 has arms of unequal length on opposite sides of the trolley 13 and that, when such trolley 13 is in vertical position, a greater portion of the contact 17 overlaps the contact 16 than overlaps the contact 15. These contacts 15 and 16 are mounted upon the locomotive frame, as best shown in Figure 1, and the contact 15 is constantly supplied with current from a suitable battery 18, carried by the locomotive, by means of a wire 19 connected to a wire 43 leading to said battery. The contact 16 is, in turn, connected to the solenoid 12 by means of the wire 41. It will thus be obvious that a break in the train circuit will cause the solenoid to be deenergized to subsequently permit the actuation of the piston rod 4.

20 The trolley 13 is designed to contact with a suitable third rail 20, as indicated in Figure 1, and, as shown in this figure, the third rail has a relatively steep incline at the rearward end and a gradually sloping incline at the forward end. The energization of the third rail 20 is, as best shown in Figure 5, controlled by a suitable semaphore 21 or by means of a trackside switch 22. The electric switch in the semaphore 21 may be of any type, suiting the preference of the user.

25 The trackside switch 22 is provided with a contactor rod 26 and, when the rail switch points are in closed position, this contactor rod will be operated by the movable rail points to connect the contacts 27 to cause the current to flow from the battery 25 to a suitable third rail 20. When the rail switch points are open in dangerous position, the contactor rod 26 will be positively moved to break the connection between the contacts 27

whereby the third rail connected to said switch will be discharged or "dead".

30 The longer arm of the contact member 17 of the trolley 13 extends rearwardly of the trolley with respect to the normal direction of the travel of the train, as best shown in Figures 1 and 3. Thus, if the trolley strikes the third rail when the train is backing up, such trolley will be moved to the right and the extended contactor will be of such length that it will serve as a connecting element between the contacts 15 and 16; therefore, when the train is moving backward the solenoid will remain energized. In order to stop a train when the engine thereof is running backwardly we provide trolley structure on the opposite side of the train that is the exact duplicate of the structure shown in Figure 1 except that the entire mechanism is reversed and is connected in series with the trolley structure shown. Therefore, the trolley structure on the opposite side of the locomotive will be ineffective when the train is moving forward but will be effective to disconnect the contact points when the train is moving backward.

35 The third rails 20 that would necessarily be placed on the opposite side of the locomotive are reversed so that the highest point is in front whereby such third rails on the opposite side of the locomotive are effective to control the operation of the solenoid when the train is moving backward.

40 When the semaphore is at safety position or when the trackside switch is closed, the current will flow to the respective third rail 20. As the circuit on the engine is broken by the trolley 13 striking the highest point on each third rail 20, the contactor 17 will be moved away from the contact 15 and the trolley 13 will pick up the current from the charged rail, which current will flow to the solenoid by way of contact 16 and wire 41 to hold the core 11 in normal position. However, when the trolley 13 strikes a "dead" 45 third rail due to either the semaphore or trackside switch being in danger position, the contactor 17 will be moved out of contact with the contact 15 and the circuit of the solenoid will be positively broken, thus allowing the solenoid 12 to become demagnetized, releasing the core 11 and allowing the air brake pressure acting on the piston 5 to move the valve cam 3 to open the valve 1 and release the air brake pressure to stop the train. If 50 the trolley 13 strikes a charged third rail, the current from the charged third rail will flow to the solenoid 12 as long as the trolley 13 is in contact with the third rail 20 but, as the train passes forward, the trolley 13 is 55 gradually returned to normal position in passing over the sloping portion of the third rail so that contact will be made between the contacts 15 and 16 before the trolley 13 moves out of contact with such third rail.

The trolley mechanism is, preferably, insulated against electrical contact with the locomotive frame in the manner best shown in Figure 4. Any preferred form of insulating material may be used to insulate the trolley pivot 14 and the spring carrier 50 but it is preferred that they be insulated as shown at 51, 52 and 53.

The forward end of the locomotive frame is provided with a casting 28 in which reciprocates a spring pressed rod 29. The lower end of this spring pressed rod 29 is provided with a brush 30, made of some suitable non-conducting material, designed to resiliently contact with the third rail 20 just in front of the pivoted trolley 13. The object of this brush is to keep the third rail clean at all times and, thus, ensure positive electrical contact between such third rail and the trolley 13.

A brush 24, made of some current conducting material, is supported by the casting 28 by means of a reciprocating spring pressed rod 23. The rod 23 is insulated as at 25 and the brush 24 is connected to the contact 16 by means of the wire 7. The brush 24 is placed directly behind the trolley 13 and makes a connection between the third rail 20 and the contact 16 in case the trolley 13 is broken or fails to function properly.

In cases where it is necessary to employ a plurality of locomotives equipped with the automatic train stopping device constructed in accordance with our invention as a part of the train, such devices on any one of the locomotives may be rendered inoperative by moving the arm 34 to close the cut-out valve 31. This arm 34 also carries the contactor 38 which connects the contacts 32 and 33 when the cut-out valve 31 is moved to closed position. By reference to Figure 1 it will be apparent that the contacts 32 and 33 are connected to the solenoid 12 and the battery 18 by the wires 43, 40 and 41 respectively, and that, when the cut-out valve 31 is closed and the contact member 38 is in contact with the contacts 32 and 33, the valve 1 is held closed and the brakes are prevented from operating.

Electrical energy normally passes from the battery 25, to and through the relay 55, to the semaphore operated switch which controls the energization of the third rail and from such semaphore operated switch, to and through the relay 55, to the third rail 20. The battery 25 is connected to the main track rail by means of the wire 56. When the semaphore operated switch is in circuit closing position current is permitted to flow to the third rail 20 whereby such third rail is energized by current from the battery 25 and, as a locomotive passes over the energized third rail, the current is picked up by the trolley 13 and is transmitted to the solenoid 12 by means hereinbefore described. The solenoid 12 is grounded to the locomotive

frame and the current passes from the locomotive frame to the main rail by way of the locomotive wheels. Thus, a complete circuit may be formed and the solenoid remains magnetized.

With reference to Figure 5, we have shown therein a track side circuit associated with the ramp 20 that is designed to be interrupted when the rail points of the switch are aligned with the side track or spur. Thus, when the switch is open, the ramp 20 will be deenergized thereby protecting the traffic approaching such switch from entering the same when open.

The track side circuit preferably consists of a battery 60, lead 63, contact 27', contact bar 65 associated with the switch lever 26, contact 27 and lead 64 to the ramp 20. The negative pole of the battery 60 is connected to one of the rails of the main line, preferably the one that is negatively charged by wire 61.

In operation, assuming that the rail points of the switch are aligned with the main line, the circuit to such ramp will be completed through wire 63, contact 27', contact bar 65 which has been moved into contact with each of the contacts 27' and 27 by the closing of the switch, wire 64 to the ramp 20. When the trolley of the locomotive circuit intercepts the charged ramp 20, current will flow through either the brush 24 to the wire 41 and thence to the solenoid 12, or will pass through the trolley arm to the contact 17, through contact 16, wire 41, solenoid 12, through the ground 62 to one of the track rails, the circuit being completed by the wire 61 extending from the negative pole of the battery 60 to the track rail.

With such an arrangement, it will be impossible for a locomotive to enter an open switch inasmuch as spreading of the rail points by the lever 26 automatically interrupts the circuit and deenergizes the ramp 20 which resultantly deenergizes the solenoid 12 of an approaching locomotive and effects the stopping of the train in a manner set out hereinbefore.

With reference to Figure 6, we have shown therein a track side circuit for energizing the ramp 20 that is controlled by one of the semaphores located at intervals along the right of way. When the signal indicates a clear track in the block wherein it is located, the ramp 20 which is set in the block behind is energized to prevent the deenergization of the solenoid 12 on the locomotive and the subsequent application of the brakes. However, should the signal indicate that the block in which it is located is occupied, the ramp 20 will be automatically deenergized and the entry of a train into such block will be prevented.

If the semaphore is of the "hand thrown type", the circuit to the ramp 20, that is operated by the semaphore 67 consists of a battery 68, lead 69, lead 71, contact 72, contact 73, bar

contact 74 operated by the lever 75 for throwing the semaphore blade, wire 76 connected to the ramp 20 and wire 77 connected between the negative pole of the battery and the negatively charged track rail in the block in which the ramp 20 is located. Thus, when the semaphore indicates a clear track, the blades will be at the vertical and the circuit will be completed to the ramp 20 by reason of the contact bar 74 closing the gap between the contacts 72 and 73. When the semaphore blade is moved to a horizontal position, indicative of an occupied block, the circuit is broken by movement of the contact bar 74 away from the contacts 72 and 73.

If the semaphore is electrically operated and controlled by a trackside system of relays, the circuit consists of the lead 69, wire 69', lever 78 operated by relay 79, wire 86 that, for the purposes of illustration, is tapped in on the wire 76, and wire 77 leading from the battery to one of the track rails. The relay 79 is placed in series with the track side relays 80 that are a part of the standard signalling system (not shown) for electrically controlling the blades of the semaphore 67. The relays 79 and 80 are connected across the track rails by means of the wire 81, and the rails are, in turn, energized by a battery 82 having a lead 83 extending to one of the rails and a lead 84 extending to the other of the rails. When the block in which the semaphore is located is unoccupied, the relay 79 is effective to close the circuit through the lever 78 and wire 86 thus energizing the ramp 20 through battery 68, wire 69, wire 69' lever 78, wire 86 and wire 76 to such ramp.

When the block in advance of that in which the ramp 20 is located is clear, the ramp 20 will be energized in the manner just set out and the locomotive may safely pass such point without having the solenoid 12 deenergized and the brakes applied. However, on entering the block in which the semaphore is located, the lead trucks will immediately short the circuit 81 to the relays 80 and relays 79. The relays 80 will operate to allow the semaphore blade to move to a danger position, and at the same time, the switch lever 78 will be released thereby breaking the circuit through the wire 86. Thus, the block in which the semaphore is located will be protected from the entry of a train thereinto by reason of the deenergization of the ramp 20 located in the block therebehind.

If desired, the trackside circuit employed with the "hand throw type" of semaphore may be combined with the ramp controlling circuit associated with the semaphore relay system and may be operated in conjunction therewith. The manner in which this may be accomplished is self-explanatory from a study of Figure 6. In the event that the semaphore should be rendered inoperative, due to some failure in its mechanical makeup,

thereby putting the circuit to the ramp out of commission, the circuit controlled by the relay will continue to function and properly protect the block.

Figure 7 shows a modified form of semaphore using a plurality of lights 46. The object of this modified form of semaphore is to dispense with the movable arm of the old type semaphore. In the modified form of semaphore, three lights extending vertically signifies a clear track, three lights extending upwardly at an angle signifies that the engineer is to proceed with caution and three lights extending horizontally signifies danger or stop.

It will be obvious that we provide an automatic train stopping device which, when a signal or the rail points of a track switch are in danger indicating position, will be effective to de-energize the corresponding third rail. This third rail causes the trolley 13 to move rearwardly to break the circuit from battery 18 and thus release the air brake pressure to stop the train. Furthermore, since the automatic train stopping device is caused to operate as a result of a de-energized third rail, in the event that the current wires leading to such third rail are grounded or broken the train will be automatically stopped irrespective of the position of the trackside switch or semaphore arm.

It will further be obvious that our novel train stopping apparatus is so constructed that operative relation between the third rails 20 and the trolley structure 13 will be assured under all conditions of speed, weather, wear, oscillation and shock. The trolley 13 will always strike the third rail 20, regardless of whether such rails are energized or de-energized and, if for any reason, the trolley 13 should stick in its oscillated position after passing the third rail, the train will be automatically stopped until the trolley is moved to its normal position to make contact between the contacts 15 and 16. It will further be apparent that the control valve 1 and the cam element 3 are pushed in one direction only by piston rod 4 and that, in order to close the valve 1 when once opened, it will be necessary for someone to manually move the valve to its closed position before the brakes may be released.

It will be understood that, as the operating valve 1 is normally closed, it must remain closed to permit running of the train.

Having thus described our invention, what we claim is:

1. Automatic train control apparatus comprising a third rail and electrical means for controlling the application of the train brakes embodying a trolley, a source of electrical current carried by the train, spaced contact plates in an electrical circuit normally adapted to prevent application of the train brakes and a contact member carried on said trolley

having a short arm extending to one contact plate and a long arm extending to the other contact plate, the said contact member being effective to maintain connection between the contact plates when the trolley passes over a third rail in one direction and to break connection between the contact plates when the trolley passes over a third rail in the opposite direction.

2. Automatic train control apparatus comprising a third rail and electrical means for controlling application of the train brakes embodying a trolley, a source of electrical current carried by the train, spaced contact plates in an electrical circuit normally adapted to prevent application of the train brakes, a contact member carried on said trolley having a short arm extending to one contact plate and a long arm extending to the other contact plate, the said contact member being effective to maintain connection between the contact plates when the trolley passes over a third rail in one direction and to break connection between the contact plates when the trolley passes over a third rail in the opposite direction, a second source of electrical current independent of the train and means for substituting said second source of current for said source of electrical current carried by the train.

3. Automatic train control apparatus comprising electrical means for controlling the application of the train brakes embodying a trolley, a source of electrical current carried by the train, spaced contact plates in an electrical circuit adapted to normally prevent application of the train brakes, a contact member carried by said trolley having a short arm extending to one contact plate and a long arm extending to the other contact plate, the said contact member being effective to maintain connection between the contact plates when the trolley passes over a third rail in one direction and to break connection between the contact plates when the trolley passes over a third rail in the opposite direction, a second source of electrical current independent of the train, a third rail section for displacing said trolley to render said first named source of current ineffective, said third rail section being effective to supply current from said second source to prevent application of the train brakes, and means for controlling the energization or de-energization of said third rail section in response to track condition.

4. Automatic train control apparatus comprising a third rail and electrical means for controlling the application of the train brakes embodying a trolley, spaced contact plates in a circuit carried by the train adapted to normally prevent application of the train brakes, a contact member carried on said trolley having a short arm extending to one contact plate and a long arm extending to the other contact plate, the contact member being ef-

fective to maintain connection between the contact plate when the trolley passes over the said third rail in one direction and to break connection between the contact plates when the trolley passes over the said third rail in the opposite direction, and a non-current conducting resilient brush structure carried by the train and contacting with the said third rail prior to the contact thereof by said trolley to effect cleaning of the third rail.

5. Automatic train control apparatus comprising a third rail and electrical means for controlling the application of the train brakes embodying a trolley, spaced contact plates in a circuit carried by the train adapted to normally prevent application of the train brakes, a contact member carried on said trolley having a short arm extending to one contact plate and a long arm extending to the other contact plate, the contact member being effective to maintain connection between the contact plate when the trolley passes over the said third rail in one direction and to break connection between the contact plates when the trolley passes over the said third rail in the opposite direction, a non-current conducting resilient brush structure carried by the train and contacting with the said third rail prior to the contact thereof by said trolley to effect cleaning of the third rail, and current conducting resilient brush structure adapted to contact with the third rail immediately after the trolley to ensure positive connection between the third rail and the brake control mechanism carried by the train.

6. Train control apparatus comprising a brake pipe system, a main air reservoir for supplying air under pressure to said brake pipe system, means operable by air pressure for releasing the air pressure from said brake pipe system and simultaneously releasing the air pressure from said main reservoir, and solenoid control means for normally preventing the operation of said brake pipe and main reservoir air pressure release means.

7. Train control apparatus comprising a brake pipe system, an engineer's controlling valve, an air reservoir for supplying air under pressure to said brake pipe system, a valve automatically adjustable in response to certain track conditions for releasing air pressure in said brake pipe system independently of said controlling valve, a fluid motor normally under fluid pressure for operating said valve, and an electro-magnet operative under proper track conditions to prevent the opening of said valve by said fluid motor, said electrical magnet being automatically releasable upon the occurrence of dangerous track conditions to permit such adjustment of said valve.

8. Train controlling apparatus comprising a brake pipe system, an engineer's controlling valve, an air reservoir, a pipe leading from

5 said air reservoir to said controlling valve, a brake pipe system leading from said controlling valve, a valve in said brake pipe system automatically operative in response to
10 track conditions to exhaust air from said brake pipe system, a second valve in communication with said pipe leading from said main air reservoir intermediate said reservoir and said controlling valve, and means responsive to operation of said first named valve to simultaneously actuate said second valve.

9. Train controlling apparatus comprising a brake pipe system, an engineer's controlling valve, an air reservoir, a pipe leading from said air reservoir to said controlling valve, a brake pipe system leading from said controlling valve, a valve in said brake pipe system automatically operative in response to track conditions to exhaust air from said brake pipe system, a second valve in communication with said pipe leading from said main air reservoir intermediate said reservoir and said controlling valve, and means responsive to operation of said first named valve to simultaneously actuate said second valve, said last named means being such that closing of said first valve will reposition said second valve.

39 In testimony whereof we hereby affix our signatures.

JAMES P. GILLIGAN.
GEORGE W. EDWARDS.
